UNITED STATES PATENT OFFICE.

WILLIAM H. NOAKES, OF CHICAGO, ILLINOIS.

SASH-BAR MACHINE.

SPECIFICATION forming part of Letters Patent No. 449,130, dated March 31, 1891.

Application filed December 24, 1890. Serial No. 375,683. (No model.)

To all whom it may concern:

Be it known that I, WILLIAM H. NOAKES, a subject of the Queen of Great Britain, residing at Chicago, in the county of Cook and State of Illinois, have invented certain new and useful Improvements in a Machine for Making Sheet-Metal Sash-Bars for Use in Constructing Ornamental Glass Windows and for other Like Purposes, of which the following is a specification.

Sheet-metal sash-bars of the class which my machine is designed to make are used in the construction of windows formed of small pieces of glass, plain or ornamental, where- with designs of greater or less intricacy are formed; and the purpose of this invention is to obtain a machine whereby a sash-bar well adapted for the purposes named may be made from a strip of sheet copper, brass, or zinc economically and expeditiously and of any required external form and shape.

I have illustrated my invention by the drawings accompanying and forming a part of this specification, wherein a machine embodying the invention and adapted to make a sash-bar of the class described is shown; but, as will be fully understood by those familiar with the art, sash-bars of this class not of the exact form, in cross-section, as the sash-bar made by this machine can be easily made in a machine embodying this invention by making slight changes in certain of the parts of the machine without departing from my invention.

Figure 1 is a side elevation of the machine; Fig. 2, a front elevation of the forward end of the machine, showing the front forming-rollers required; Fig. 3, a front elevation of the second set of forming-rollers back of the front forming-rollers; Fig. 4, a front elevation of a hollow former forming a part of the machine; Fig. 5, a rear elevation of such former; Fig. 6, a longitudinal section thereof; Fig. 7, a bottom plan view of the inside form required in the former; Fig. 8, a top plan view of such central form; Fig. 9, a front elevation of the rear and finishing former-rollers of the machine; Fig. 10, a cross-section of the sash-bar sheet-metal strip from which the sash-bar is made in this machine, and Fig. 11 a cross-section of a completed sash-bar.

In the operation of this machine a strip of thin sheet metal of the proper width to make

the sash-bar illustrated in Fig. 11 of the drawings hereof, which strip may be of about one and three-eighths inch in width, is inserted 55 between the front forming-rollers of the machine. (Illustrated in elevation in Fig. 2.) Such strip of sheet metal then passes between the set of forming-rollers next back of the first-named set, and from the second set of forming-rollers the partially-formed sash-bar extends through the hollow former shown in Figs. 5, 6, 7, and 8, and from thence through the finishing-rollers, (illustrated in Fig. 9,) emerging therefrom a completed sash-bar of 65 the shape illustrated in cross-section in Fig. 11. The forming-rollers are driven by a wheel rigidly secured to the shaft of one of the rollers and by gearing intermeshing with a gear on the driven-shaft extending therefrom to 7c the several forming-roller shafts.

Like letters refer to similar parts throughout the several views thereof.

X is the base of the machine.

A A are the standards of the front set of 75 forming-rollers. B B are the standards of the second set of forming-rollers. C is the standard of the stationary former, and D is the standard of the last and finishing rollers of the machine. These several standards A, B, 80 and C are all rigidly secured to the base X; but the standards D D are adjustable on such base X.

A' A² are the shafts of the front set of forming-rollers E E', which are respectively secured rigidly on such shafts A' A².

e is the face of forming-roller E, which in cross-section, has approximately the form of the reverse or under side of the sash-bar made in the machine, and e' the face of the upper 90 roller, which has in cross-section approximately the form of the obverse or inside face of the central part of the sash-bar made in the machine. To avoid cutting the strip of sheet metal from which the sash-bar is being made 95 as such strip passes between the front rollers, the face of such front rollers can only approximate in cross-section the form ultimately to be obtained in such sash-bar.

B' B² are the shafts of the second set of forming-rollers F F'. Forming-rollers F F', respectively, are secured rigidly on the shafts B' B².

f is the face of forming-roller F, which in

cross-section is approximately (and much more nearly so than is the face *e* of forming-roller *E*) the same as the reverse or under side of the sash-bar made in the machine, and 5 *f'* is the face of the upper roller *F'*, and this in cross-section is very nearly the form of the obverse or inside face of the central part of the sash-bar made in the machine.

Forming-rollers *F F'* are so adjusted in reference to the thickness of the sheet of metal passing between them as to force the partially-formed sash-bar through the hollow former *G* and between the forming-rollers *F F'* and the finishing-rollers *H H'*. The hollow former *G* is composed of the two outside pieces *g* and *g'* and the central form or core *G'*.

*g*² are projecting prongs from the main body of the form *G'*, and these prongs *g*² extend in between the finishing-rollers *H H'*. The extent to which these prongs extend into the open space between the peripheries of the rollers *H H'* is determined by the thickness of the sheet metal of which the sash-bar is being made, sufficient space being left around 25 the prongs and between them and the periphery of the forming-rollers *H H'* to allow the metal to pass between.

h is the face of the forming-roller *H*, and *h'* is the face of the forming-roller *H'*, and it 30 will be observed that the parts of these faces *h h'* which come in contact with the sash-bar passing between them are identical with each other in form and are of the exact shape of the completed sash-bar illustrated in Fig. 11 of 35 the drawings and lettered *I*.

i is the strip of sheet metal (illustrated in Fig. 10) of which the sash-bar *I* is formed or bent up. The face *h'* of forming-wheel *H'* is in cross-section the form of the obverse 40 side of the sash-bar, and the face *h* of forming-wheel *H* is in cross-section the reverse side of the sash-bar, and if it is desired to vary the two sides of the sash-bar it will be necessary to construct the face of the forming-rollers *H H'* to be identical therewith, and also the cross-section of the prongs *g*² of the inside form *G'* must be changed.

The thickness of the sheet of metal of which the sash-bar is constructed may be varied, 45 and the several forming-rollers *A', A², B', and B²*, the two parts *g g'* of the inside former *G*, the position of the inside form *G'* in the hollow former *G*, and the rollers *H H'* can all be adjusted to correspond with such thickness 55 of metal. For the purpose of this adjustment the following means have been provided: The several shafts *A' A², B' B²*, and *D' D²* of the forming-rollers revolve freely in boxes *J J'*, respectively. These boxes *J J'* move 60 vertically in slot *K* of the several standards. *K'* is a cap secured to the top of the standards *A, B*, and *D*, respectively, and *L L* are set-screws extending through the cap *K'* and against the journal *J'*. By turning the set-screws *L* journals *J'* may be forced upward 65 by the metal passing between the forming-rollers on the several shafts, and the required

adjustment is thus secured. *M* is a set-screw in part *g'* of the hollow former *G*, which can be forced downward by turning it, thereby forcing downward the forward end of the inside form *G'*. *M' M'* are screws uniting the parts *g g'* of the hollow former *G*. Such screw *M'* fits loosely in the hollow therefor in part *g* of the former and has a thread *m* cut on 75 the upper end thereof, fitting into a thread in the hole provided therefor in part *g'* of the former. The extent to which the prongs *g*² of the inside form *G'* extend between the rollers *H H'* is determined by the sliding 80 movement of the standard *D* on the base *X*, and this sliding movement is controlled by the set-screw *N*, fitting into the standard *n* on the base *X* and having a screw-thread fitting into a corresponding screw-thread *n'* in standard *D*. A strengthening-rod *I'* can be inserted in the hollow *I*² of the sash-bar *I*, if desired, in order to strengthen the sash-bar. An iron bar of the shape in cross-section of this hollow *I*² can be run through the machine along with the sheet-metal strip *i* by taking out the form *G'* in the hollow former *G*, and in such case in the completed sash-bar the hollow *I*² will be filled with this bar, the sheet metal being pressed closely thereto.

Having thus described my invention, what I claim, and desire to secure by Letters Patent of the United States, is—

1. The combination of a hollow former consisting of two blocks having grooves therein 100 adjustably held together, whereby an adjustable former having a flaring mouth at the receiving end and a smaller mouth at the delivery end thereof is obtained, with a form suspended at one end thereof in the 105 hollow former near the receiving end of such hollow former, such form extending beyond the delivery end of the hollow former and having prongs thereon adapted to extend within a hollow space to the sides of that portion of the periphery of forming-rollers rotatably held in a frame therefor, which grasp the center of the strip of sheet metal passing through the former and between such rollers, whereby the external and internal shape of 110 a strip of sheet metal forced through the adjustable hollow former is determined by such hollow former and form therein, and the forming-rollers and prongs extending between them, substantially as described.

2. The combination of the hollow former *G*, provided with a flaring mouth or opening at one end thereof, the form *G'*, suspended at one end thereof in the hollow former *G* by adjustable screw *M*, the form *G'* extending beyond the hollow former at one end thereof and such extension provided with prongs adapted to extend into the hollow space between the periphery of forming-rollers rotatably held in a frame therefor, whereby the 125 external and internal shape of a strip of sheet metal forced through the hollow former is determined by such hollow former and form therein, and the forming-rollers and prongs

extending between them, substantially as described.

3. In a machine for making sheet-metal sash-bars for constructing ornamental glass windows, the combination of adjustable forming-rollers, between which a strip of sheet metal passes, forming-rollers behind the first-named forming-rollers, between which also the partially-shaped sash-bar passes, a flaring hollow former through which the partially-shaped sash-bar is forced, a form suspended within the hollow former near the large end thereof, such form having prongs thereon extending beyond the hollow former to forming-rollers behind such form, and forming-rollers between which the sash-bar passes, and by which, in combination with the prongs of the form, the completed external shape of the sash-bar and the internal shape of the hollow sides thereof are given thereto, substantially as described.

4. In a machine for making sheet-metal

sash-bars for constructing ornamental glass windows, the combination of adjustable forming-rollers between which a strip of sheet metal passes, adjustable forming-rollers, behind the first-named forming-rollers, between which also the partially-shaped sash-bar passes, an adjustable hollow former through which the partially-shaped sash-bar is forced, a form adjustably contained within the hollow former, having prongs thereon extending therefrom to adjustable forming-rollers behind such form, and adjustable forming-rollers behind such adjustable form, between which last-named forming-rollers the sash-bars pass and by which the completed external shape thereof is given thereto, substantially as described.
